Primary Examiner — Kevin K Rudzinski*Assistant Examiner* — Richard E Yenchesky(74) Attorney, Agent, or Firm — Warner Norcross + Judd LLP(57) CLAIM

The ornamental design for a tray for a floor cleaner, as shown and described.

DESCRIPTION

FIG. 1 is a front, right side perspective view of a tray for a floor cleaner showing our new design;

FIG. 2 is a front, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The details of the tray for a floor cleaner shown in broken lines form no part of the claimed design.

1 Claim, 6 Drawing Sheets(56)
